UNITED STATES PATENT OFFICE.

LEON H. PRENTICE, OF WAUKEGAN, ILLINOIS.

STEAM-RADIATOR.

SPECIFICATION forming part of Letters Patent No. 313,883, dated March 17, 1885.

Application filed June 24, 1884. (No model.)

To all whom it may concern:

Be it known that I, LEON H. PRENTICE, of Waukegan, in the State of Illinois, have invented certain new and useful Improvements 5 in Steam-Radiators, of which the following is a specification.

The invention relates to steam-radiators used for warming offices and apartments of buildings; and it consists in the construction, arrangement, and combination of parts, herein-after described and claimed, for regulating the heat.

The accompanying drawings illustrate the invention.

15 Figure 1 is a side elevation of a steam-radiator containing the invention, portions being broken away to show the interior construction. Fig. 2 is a sectional plan view of the same. Fig. 3 is a top view of a portion of the 20 radiator. Fig. 4 is an enlarged sectional plan view of a portion of the same.

A A' A" designate the heaters. B is the base, and B' the top. The base, as represented, is formed of three independent compartments, b b' b", having no communication with each other, and the heaters A A' A" connect and communicate, respectively, with the compartments of the base, so that the heaters A, with the compartment b of the base, and A' b', 30 &c., constitute each distinct parts of the radiator independent of each other.

C is the pipe for conducting the steam to and into the radiator. A valve, C', is placed at the junction between the pipe and the radiator, and three ports, a a' a", connect the compartments b b' b", respectively, with the pipe through the same valve C'. The valve is hollow and open at the bottom, and has a wide side opening, c c, sufficient to cover all the 40 ports at once. The valve is preferably made tapering and compressed by a spring, s, into its seat of corresponding taper for compensating wear. An operating-rod, D, is connected with the valve and provided with a handle, 45 D', and a dial, E, and index e are attached to show the position of the valve, as when closed or open, or having one or more of the compartments open. A spring-pawl, e', engaging with notches e" in the edge of the dial-plate, is 50 provided for setting or fixing the valve in any of its desired positions.

The drawing, Fig. 1, shows the operating-rod extended up through one of the end heaters and through the top B', with the dial on the top. With this construction the valve 55 should be open at the top, as at c', to allow the steam to pass up into the heater having the rod thus extended up through it. When the valve is made tapering and seated in a tapering seat, as shown, it is also necessary 60 to have this opening c', to prevent the steam-pressure from compressing the valve so tightly in its seat as not to be easily turned. The steam from pipe C passes through the valve-opening c c, and thence through the ports a a' 65 a" into the compartments b A b' A' b" A". Moving the handle D' to the extreme left or notch nearest "closed," (marked on the drawing, Fig. 3,) turns the opening c c away from all the ports and closes all of them. Moving 70 it thence to the right one notch opens the first port, a, and heats only the corresponding compartment b A. Moving it one notch farther opens the second port, a', without closing the first, so that an additional compartment 75 is heated, and so on until all the ports are open and the whole radiator is filled with steam and heated. By a reverse movement of the handle the steam is shut off from one or more of the compartments, as desired, after 80 the room has been sufficiently warmed to require only one or more or less than all of them to maintain the temperature without increasing it.

I am aware that steam-radiators made in 85 two or more compartments and having a separate valve for letting steam into each compartment have heretofore been used; but this construction does not constitute my invention, which consists in the combination of a radiator with one or more compartments with a single valve located between the junction of the inlet-pipe and the radiator and connected with a separate port for each compartment of the radiator, whereby the whole or one or more 90 of the compartments may be operated by the single valve in such manner that only a portion of the radiators may be used in mild weather, when only a little warmth is required, and a greater portion or all of them at other 95 times when more warmth is required, and the radiator may be made with two or any greater 100

number of compartments, the one valve governing them all being made to correspond and operate in connection with a steam-port from the inlet-pipe to each of the compartments 5 through the one valve, and the dial being made to correspond.

The arrangement of the handle of the valve on the top by running the rod D up through one of the radiator-pipes, as shown in Fig. 1, 10 is a new and convenient arrangement; but the valve may be located outside of the base at the end, and the operating handle and dial be placed at the bottom without materially changing the combination of the single valve with 15 a compartment-radiator.

What I claim is—

1. As an improvement in steam-heating apparatus, the radiator composed of two or more independent compartments, each having a 20 separate port, in combination with an inlet-pipe, as C, and a single valve, as C', operating in connection with all the ports, substantially as and for the purpose specified.

2. As an improvement in steam-heating apparatus, the radiator composed of two or more 25 independent compartments, each having a port, in combination with a single inlet and valve and a dial, as E, substantially as and for the purpose specified.

3. As an improvement in steam-radiators, 30 the valve, as C', in combination with the rod, as D, extended up through one of the radiator-pipes to the top of the radiator, and having a handle and a dial, as E, all arranged substantially as shown.

4. The steam-radiator having compartments b A, b' A', and b" A", inlet-pipe C, valve C', operating-rod and handle D D', and dial E, 35 all constructed and arranged substantially as shown.

LEON H. PRENTICE.
